[57] CLAIM

The ornamental design for a combination camera and accessory case, as shown and described.

DESCRIPTION

FIG. 1 is a top front and left side perspective view of a combination camera and accessory case showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view showing the lid open; and

FIG. 9 is a top, rear and left side perspective view of a second embodiment of the combination camera and accessory case shown in FIG. 1.
